CLAIM

The ornamental design for a toboggan of flexible plastic sheet material, as shown and described.

DESCRIPTION

FIG. 1 is a front perspective view of a toboggan showing my new design;

FIG. 2 is a left side elevational view thereof, the right side elevational view being a mirror image of that shown; and,

FIG. 3 is a rear elevational view thereof.

FIG. 1**FIG. 2****FIG. 3**
